PURCHASES MILES, OF NEW YORK, N. Y.

Letters Patent No. 63,169, dated March 26, 1867; antedated March 15, 1867.

IMPROVED CURTAIN FIXTURE.

The Schedule referred to in these Letters Patent and making part of the same.

TO ALL WHOM IT MAY CONCERN:

Be it known that I, PURCHASES MILES, of the city and State of New York, have invented, made, and applied to use a certain new and useful improvement in Curtain Fixtures; and I do hereby declare the following to be a full, clear, and exact description of the said invention, reference being had to the annexed drawing, making part of this specification, wherein—

Figure 1 is an elevation of my improvement applied at one end of a curtain roller.

Figure 2 is a detached plan of the cord-holder.

The same letters refer to corresponding parts.

Curtains have been mounted upon a roller, at the end of which is a spool upon which a cord is wound as the curtain runs down by its own weight or a weighted slat, and the reverse movement draws up the curtain. In this mode of fitting, the cord has sometimes been weighted so as to counterpoise the curtain, and ratchets and pawls operated upon by the cord have also been employed.

The nature of my said invention consists in a slotted cord-holder to take knots, projections, or inequalities in the cord and prevent the roller turning by the weight of the curtain.

In the drawing, *a* represents a portion of the window-casing, *b* the curtain, *c* the roller, *d* the spool, and *e* the brackets, of any desired character. *f* is the cord attached at one end to the spool *d* so as to wind up the spool by the descent of the curtain, or wind up the curtain by the rotation of the roller in drawing off the said cord *f*. *g* is my cord-holder formed as a slot, with an eye, 2, near the end, and 1 1 are knots or projections in the cord *f*. It will now be understood that when the curtain is to be raised or lowered the cord *f* is to be held so that it passes freely through the eye 2, but when the curtain is to be held in place, the cord is to be moved into the slot of the holder *g*, and one of the knots or projections 1, drawing up against the under side of said holder *g*, prevents the further descent of the curtain.

What I claim, and desire to secure by Letters Patent, is—

The cord-holder *g*, in combination with a cord for curtain fixtures, upon which cords are knots or projections, substantially as and for the purposes specified.

In witness whereof I have hereunto set my signature this eleventh day of August, 1866.

PURCHASES MILES.
